UNITED STATES PATENT OFFICE.

FRED LINCOLN HEWITT, OF WINCHENDON, MASSACHUSETTS, ASSIGNOR TO M. E. CONVERSE & SON CO., OF WINCHENDON, MASSACHUSETTS, A CORPORATION OF MASSACHUSETTS.

REFRIGERATOR.

1,327,473.

Specification of Letters Patent.

Patented Jan. 6, 1920.

Application filed December 31, 1918. Serial No. 269,071.

To all whom it may concern:

Be it known that I, FRED L. HEWITT, a citizen of the United States, and a resident of Winchendon, in the county of Worcester and State of Massachusetts, have invented a new and Improved Refrigerator, of which the following is a full, clear, and exact description.

The invention relates to refrigerators of the household type and irrespective of the location of the ice compartment.

The object of the invention is to provide a new and improved ice refrigerator having an outer box, an inner box spaced from the outer box, and partitions interposed between the walls of the said boxes to provide double air spaces between the walls of the boxes thereby dispensing with fillings of insulating materials such as sawdust, asbestos, fibers and the like. Another object is to permit of forming the interior and exterior boxes individually and completely and to allow of assembling the boxes to hold the same in spaced relation without the use of 20 nails, screws or similar fastening devices or special fittings. Another object is to permit of conveniently and quickly assembling the boxes without the employment of skilled labor thus allowing manufacturing of the 25 refrigerator at a comparatively low cost.

With these and other objects in view the invention consists of certain novel features of construction as hereinafter shown and described and then specifically pointed out in 30 the claims.

A practical embodiment of the invention is represented in the accompanying drawings forming a part of this specification in which similar characters of reference indicate corresponding parts in all the views.

Figure 1 is a sectional side elevation of the improved refrigerator in the form of an ice chest;

Fig. 2 is a sectional plan view of the same 45 with the inner box removed;

Fig. 3 is a cross section of the same;

Fig. 4 is a transverse section of the improved refrigerator having the ice compartment in the top;

Fig. 5 is a sectional perspective view of a portion of one corner of the refrigerator; and

Fig. 6 is a perspective view of a portion

of the spacing and holding members partly disassembled.

The refrigerator illustrated in Figs. 1, 2 and 3 is in the form of an ice chest having an outer box or a casing 10 supported at its bottom on legs 11 provided with casters 12 adapted to rest on a floor 13 or other support. Within this outer box 10 and spaced therefrom is arranged an inner box 15 preferably provided with a sheet metal lining 16 and adapted to be closed by a cover 17 connected at its rear end by hinges 18 with a top board 19 forming part of the outer box 10. A cover 20 is connected by hinges 21 with the top board 19 to close the top of the outer box 10, as will be readily understood by reference to Figs. 1 and 3.

In order to hold the inner box 15 spaced from the outer box 10 use is made of vertically and horizontally disposed spacing and holding members 25, 26, of which the vertical spacing and holding members 25 fit onto the vertical interior angles of the outer box 10, and the horizontal spacing and holding members 26 fit onto the interior horizontal angles of the outer box 10 and abut against the lower ends of the vertical spacing and holding members 25, as will be readily understood by reference to Figs. 5 and 6. The vertical and horizontal spacing and holding members 25 and 26 are provided at their inner edges with rabbets 27 and 28 onto which fit the arris of the inner box 15 thus spacing the inner box 15 from the outer box 10 and holding the inner box in position within the outer box without the use of nails, screws or other similar fastening devices. It will be noticed that by the arrangement described the outer and inner boxes 10 and 15 can be individually manufactured and the spacing and holding members can be readily placed in position in the outer box 10 and then the inner box 15 can be readily placed in position on the said spacing and holding members 25 and 26.

Each vertical spacing and holding member 25 is provided on its inner side with vertically disposed grooves 30 and 31, and the horizontal spacing and holding members are provided at the top and the inner sides with horizontal grooves 32, 33, of which the grooves 32 register with the grooves 30 and 31 while the grooves 33 register with each

other. The registering grooves 30 and 32 are engaged by partitions or walls 40, and a similar partition or wall 41 fits into the registering grooves 33 whereby the partitions 40 and 41 are held spaced between the corresponding walls of the outer and inner boxes 10 and 15, thus providing between corresponding walls double air spaces, as plainly indicated in Figs. 1, 2 and 3. It will be noticed that the partitions 40 and 41 together with the spacing and holding members 25, 26 form a third or insulating box intermediate the outer box 10 and the inner box 15. It will further be noticed that the vertical and horizontal spacing and holding members 25 and 26 when assembled form the frame of the insulating box and securely hold the partitions or walls 40 and 41 in place and at the same time the said frame forms a support for the inner box 15.

The vertical spacing and holding members 25 extend from the bottom of the outer box 10 to within a distance of the top of the said box and the top of the inner box 15, and the horizontal spacing and holding members 26 abut against the lower ends of the said vertical spacing and holding members 25 to hold the spacing and holding members firmly in position within the outer box, thus holding the inner box 15 in position without the use of nails, screws or other fastening devices. The tops of the partitions 40 are flush with the upper ends of the vertical spacing and holding members 25. A sealing frame 50 fits onto the top of the inner box 15 and extends over the partitions 40 and the members 25 and abuts against the inner faces of the walls of the outer box 10 thus closing or sealing the upper ends of the air spaces formed by the vertical partitions 40.

In the ice chest above described and shown in Figs. 1, 2 and 3 the outer and inner boxes 10 and 15 are open at the top while in the refrigerator shown in Fig. 4 the outer and inner boxes 60 and 61 are open at the front and the inner box 61 is provided with a horizontal partition 62 dividing the inner box into an upper or ice compartment 63 and a lower or storage compartment 64. The compartments 63 and 64 are adapted to be opened and closed by suitable doors 65 and 66. The general construction of the boxes 60 and 61 is the same as above described in reference to the ice chest and similar vertical and horizontal spacing and holding members 25 and 26 are provided and likewise partitions 40 and 41 to provide double air spaces between the corresponding walls and the inner and outer boxes 60 and 61.

As this construction is exactly the same as the one above described it is not deemed necessary to further describe or illustrate such construction.

It will be noticed that I do not limit myself to the particular type of refrigerator as

the improvements above set forth are readily applicable to refrigerators of the household type and irrespective of whether the location of the ice compartment is at the bottom, the top or at one end.

In practice the outer and inner boxes 10 and 15 are constructed separately and the spacing and holding members are cut to proper length from a strip or bar provided with the rabbet and the two grooves. The 75 spacing and holding members are readily placed in position in the outer box. The partitions are next placed in position in the grooves after which the inner box 15 is inserted in the outer box 10 with the arris fitting the rabbets of the vertical and horizontal members. If the refrigerator is in the form of an ice chest then the sealing frame is next placed in position and fastened down by nails if desired. The covers 17 and 20 85 are next attached to complete the ice chest.

If the refrigerator is in the form shown in Fig. 4, the parts are assembled practically in the same manner as above described but the frame is dispensed with and spacing and holding members are used instead to seal the fronts of the air spaces, as will be readily understood by reference to Fig. 4. The doors 65 and 66 are hinged on a door frame 67 fitting into the registering front openings 95 of the outer and inner boxes 60 and 61.

It is understood that in assembling the outer box, the inner box and the intermediate or insulating box they become locked in place by frictional contact of the members and without the use of nails, screws or other fastening devices and which devices are liable to form heat conductors especially upon passing through the air spaces thus spoiling the insulating efficiency.

The boxes are preferably made of wood but other non-conducting materials such as fiber boards and the like may be used.

Having thus described my invention, I claim as new and desire to secure by Letters Patent:—

1. A refrigerator, comprising an outer box, an inner box and an insulating box intermediate the said outer and inner boxes, the outer and inner boxes being unitary rigid structures and the insulating box being made of walls, and a sectional frame having means for receiving and holding the said walls whereby the use of nails or the like is obviated, the frame fitting into the 115 outer box and forming a support for the inner box.

2. A refrigerator, comprising an outer box, an inner box, and spacing and holding members detachably fitting onto the interior angles of the outer box and provided with rabbets into which fit the arris of the said inner box to hold the latter spaced from the outer box, to retain the spacing and holding members in position and to 130

hold the inner box in position by frictional contact.

3. A refrigerator, comprising an outer box, an inner box, spacing and holding members fitting onto the interior angles of the outer box and provided with rabbets into which fit the arris of the said inner box to hold the latter spaced from the outer box and to hold the inner box in position 10 by frictional contact, the said spacing and holding members being provided with grooves parallel to the said rabbets, and partitions fitting into the said grooves and extending between the walls of the said 15 outer and inner box to provide double dead air spaces.

4. A refrigerator, comprising an outer box, an inner box, the boxes having registering openings, spacing and holding bars 20 fitting the inner angles of the said outer box and provided with rabbets engaged by the arris of the said interior box, the said spacing and holding bars being provided intermediate the said boxes with grooves, 25 and partitions fitting the said grooves and extending between the corresponding walls of the said outer and inner boxes to provide double air spaces between such walls.

5. A refrigerator, comprising an outer box, an inner box, the boxes having registering openings, spacing and holding bars fitting the inner angles of the said outer box and provided with rabbets engaged by the 30 arris of the said interior box, the said spac-

ing and holding bars being provided in- 35 termediate the said boxes with grooves, partitions fitting the said grooves and ex- tending between the corresponding walls of the said outer and inner boxes to provide double air spaces between such walls, and a 40 sealing means extending over the said partitions and the said dead air spaces to seal the latter.

6. A refrigerator, comprising an outer box, the boxes having regis- 45 tering openings, spacing and holding bars fitting the inner angles of the said outer box and provided with rabbets engaged by the arris of the said interior box, the said spacing and holding bars being provided in- 50 termediate the said boxes with grooves, partitions fitting the said grooves and ex- tending between the corresponding walls of the said outer and inner boxes to provide double air spaces between such walls, the 55 walls of the outer box projecting beyond the walls of the inner box at the said regis- tering openings of the said boxes and the partitions having their free edges substan- tially flush with the arris of the inner box, 60 and a sealing frame fitting onto the opening edge of the walls of the inner box and ex- tending over the said partitions and the said air spaces and abutting against the in- 65 ner faces of the projecting portions of the walls of the outer box.

FRED LINCOLN HEWITT.
